BUILDING BLOCK

Charles L. Sanford, Meadville, Pa.

Application April 7, 1932, Serial No. 603,842

7 Claims. (Cl. 72—44)

This invention relates to concrete blocks for building purposes and more especially to concrete blocks designed for use in the formation of outside walls which are exposed to frost and weather. There are several requisites which should be present in a wall formed of blocks. One of these is, of course, that the wall shall have full necessary strength. Another is that the wall shall be double, not merely provided with vertical flues, but formed with an air space which is practically continuous and extends across the joints between the blocks so that there will be no conductive mass extending through the wall to the rear thereof and thus so that the wall shall be frost-proof and shall neither conduct heat from the interior of the house to the exterior or cold from the exterior of the house to the interior.

It is further necessary that the two masses or thicknesses of the double wall shall be securely tied to each other and that the ties shall be so formed that the wall element or block shall resist thrusts in any direction. It is further necessary that the element or block shall be so formed as to secure wide confronting surfaces for the application of bonding material or mortar and that the wall element shall be as light as possible without detracting from its strength.

It is further desirable that while the body of the element or block shall be of relatively strong material, the face of the block shall be of material having an ornamental value and that there shall be a minimum of space between the confronting edges of the outer ornamental faces of the block.

It is further desirable to so form the inner portion of the block that furring strips, laths and framing may be readily nailed to the inner surface of the block.

With these requisites in view, I have devised a building block or element which comprises two spaced, parallel and non-contacting members connected by metallic ties, these ties being so formed as to secure not only great resistance to longitudinal stress but so formed as to secure great strength against bending stresses.

A further object is to provide a building block which is so formed that it provides a non-frost conducting uniting means and an air space entirely separating the outside and inside walls or members of the block.

A further object is to provide a concrete block which will be much stronger than the ordinary concrete block and will be suitable for walls requiring increased strength.

Another object is to provide a block which will be fire-proof, inexpensive to manufacture, easy to build into a wall, thoroughly adapted to the purposes for which it is intended, very durable and capable of having a wide variety of designs for the outside face of the block, and another object is to provide a block which is so formed that a relatively large space is left within the wall within which electric wiring conduits, water pipes, heating pipes and the like may be disposed.

My invention is illustrated in the accompanying drawing, wherein:—

Figure 1 is a top plan view of a building block, constructed in accordance with my invention;

Figure 2 is a vertical sectional view through a wall constructed of these building blocks;

Figure 3 is a fragmentary face view of the building block;

Figure 4 is a fragmentary elevation of one of the end tie strips between the front and rear sections of the block.

Referring to the drawing, it will be seen that my block comprises an outer portion or member 10 and an inner portion or member 11. The outer portion 10 is formed of relatively dense concrete while the inner portion 11 is preferably formed of cinder concrete. The inner member 11 is reduced in thickness longitudinally as at 12 so that the upper and lower ends of the member 11 are relatively thick as at 13. The same is true of the member 10 which is also reduced in thickness at its middle as at 12 and has the relatively thickened upper and lower portions 13.

Formed integrally with the member 10 is the facing portion 14 of the block which may be made of terra-cotta, imitation marble, ornamental concrete, slabs of different kinds of stone or any material desirable to use, this facing portion 14 being integrally connected to the member 10 at the time that the member 10 is formed.

Connecting the members 10 and 11 are the ties or reinforcing members 15. I do not wish to be limited to the particular form, construction or material of these ties, but preferably these ties will be formed of copper bearing steel, galvanized to provide a wall uniting means which will be both rust-proof and moisture-proof and will stand extremely high heat. I have shown four of these ties 15 disposed between the front and rear portions of the block but I do not wish to be limited to this number. These ties are disposed in horizontal planes and preferably consist each of a longitudinally corrugated strip, the extremities of the strip being preferably perforated as at 16. Preferably, the burr caused by perforating

- the strips will be left to project from the strips so that this burr will also act to anchor the strips within the bodies 10 and 11 of concrete. The tie members are given rigidity by the longitudinal corrugations which run the entire length of these members. The opposite ends of these members extend into and are cast into the relatively thick portions 13 of the outer and inner members of the block.
- As will be seen from Figure 2, the facing portion 14 of the block extends beyond the upper and lower faces of the ends 13 of the member 10. The relatively wide faces of the portions 13 of the block provide for the blocks being bonded to each other by a relatively wide and thick bonding of mortar, concrete or other material designated 17.

By extending the facial portion 14 of the block beyond the portions 13, the facial portions of the block may be laid either directly against each other or separated by a relatively narrow space as shown in Figure 2. This provides for a narrow joint 18 at the surface of the wall while a full amount of bonding material such as mortar will be used between the blocks back of these extensions of the facial portion. The pointing mortar 19 of the wall between the closely approximated edges of the facial slabs 14 may be of any color desired, as for instance, a color to match the facial slab 14. The facial slab portion 14 secures greater strength for the outside wall and thus provides reinforcing means not found in the ordinary concrete block. As before stated, the inside wall or member 11 of the block is made of a solid cinder block or made of suitable material similar to cinder block which readily permits nails to be driven into any portion of it without damage. Thus casings, baseboards, mouldings, etc., may be readily nailed to the inside face of the block and such cinder block forms an excellent surface over which to plaster, insuring no shrinking or cracking of the plaster, and providing a smooth and even surface therefor.

My block is so constructed that it is not necessary to strip and lath the inner surface before plastering in order to prevent dampness caused by frost penetrating the solid portions of the block. This is entirely overcome by the provision of an air space between the two sections of the block, which air space extends continuously from the top of the block to the bottom and from one end of the block to the other end.

Thus a wall formed of these blocks is in effect a double wall connected at intervals by ties, but in my case, these ties are integrally embedded in the outside and inside elements of the hollow wall and thus there is no possible danger of this inside and outside element separating or becoming untied or unbonded. In a wall constructed of the blocks as heretofore described, there is no conduction of heat or cold from one surface of the wall to the other because the dead air space is continuous throughout the entire wall. These blocks have been tested in actual practice and it has been found that by corrugating the sheet metal ties 15, this so strengthens these ties that the blocks may be dropped from a considerable height without bending the ties or distorting them and without any damage to the blocks themselves. These ties will resist thrust or stress in any direction. Their corrugated form will resist thrust longitudinally of the tie, so stiffens the tie that it cannot be bent and, of course, resists any lateral movement of one section of the wall relative to the other section of the wall.

Blocks constructed in accordance with my invention save both labor and material in constructing a building and will provide for a wide range of ornamentation or outside appearance for different classes of buildings and walls. The 5 block is a poured block, very much stronger than any dry-pressed block, and further the block is reinforced by the insertion of the corrugated metallic strips.

A particular advantage of my block resides in 10 the fact that while the upper and lower faces of the front and rear sections have considerable width so as to secure a good bearing upon the block below and provide a good bearing for the block above, the middle portion of each section 15 being greatly reduced in thickness as at 12, provides for the ready insertion of soil pipes, wiring, gas pipes, heating pipes and the like. The total thickness of the block composed of the two sections is very important. Without the upper and 20 lower thickened portions such as I use, with my block, two plain sections of a block would have to be too thick to secure sufficient strength and sufficient bearing surfaces and would not permit of sufficient wide air space between them to receive a standard soil pipe. In my block, the two sections are spaced from each other, the middle portions of the two sections are reduced in thickness and the tie members 15 are likewise spaced from each other so that a full air space is provided from one end of the wall to the other and from the bottom of the wall to the top and a full space is thus provided for the passage of pipes, electric wiring, etc.

It is to be noted that the thickened portions 35 13 of the block extend from end to end for the entire length of the block and have no broken places or interruptions which would require the ties 15 to be disposed within certain very definite limits. My relatively wide tie members are embedded in the thickened portions of the block and may be placed anywhere from end to end of the block, as convenience dictates, without any changes in the shape of the sections or the forms in which they are made. These thickened portions 40 13 extending the entire length of the block provide wide mortar beds, reinforce the walls of the block, and provide for a wide range of adjustment of the tie members, if required. The wide corrugated metal ties used by me cause the sections to be held rigidly with relation to each other at both the top and bottom of the block and these four relatively wide tie members hold the two sections from any possible displacement while at the same time the tie members are light and may 45 be cheaply constructed and readily inserted in the mold. Inasmuch as the tie members are corrugated, they may be made of sheet material and readily stamped out and because of the corrugations, the sheet metal is sufficiently stiffened 50 as against all bending strains or stresses.

The use of a cinder concrete section for the section 12, that is the inner section, is of great importance as it accomplishes several important objects. By its nature in connection with an unbroken air space between it and the outer section, the cinder block section makes the inner wall surface secure from frost and dampness and provides a flat, smooth surface to which plaster will be directly applied without the use of strips and 65 laths. The cinder block section makes it unnecessary to use wood blocks inserted in a wall to which to nail or otherwise secure inside finish material or appliances. Such a block is easily cut away or drilled through for openings permitting 70 75

the passage of conduits and pipes and provides a wall which with the unbroken air space is practically sound-proof. At the same time, the cinder section is sufficiently wide or thick at its upper and lower ends as to secure thoroughly good anchoring engagement with the ties. It will be noted that the facing 14 may be readily cast integral with the outer section 11 and is not merely applied to this outer section. Of course, it may be formed of the same concrete as the outer section itself or of a different character of concrete or like material having an ornamental character. Inasmuch as it is integral with the outer section of the wall, it cannot crack or break away due to the action of frost or due to the action of heat. At the same time, extending as it does beyond the edge faces of the outer section of the block, it provides for relatively narrow joints between the block sections.

20 I claim:—

1. A building block formed of two parallel sections spaced from each other throughout their entire extent and metallic ties embedded in the ends of said sections, the outer section being formed of relatively dense and hard concrete, the inner section being formed of concrete permitting the driving of nails thereinto.

2. A building block formed of two sections of concrete, the sections being disposed in parallel relation to each other and spaced throughout their entire extent, longitudinally corrugated sheet metal ties disposed between the ends of the sections and embedded therein and extending across the space between the sections, the upper and lower edges of the sections having relatively wide mortar receiving faces, the middle portions of the sections upon their confronting faces being longitudinally recessed from end to end for their entire length, the front section having integrally 40 connected thereto a slab of different material, the slab projecting beyond the side and end faces of the front section whereby when the blocks are placed together to form a wall, the slabs may be disposed with their edges in close approximation while the side and end edges of the bodies of the front sections will be spaced from each other sufficient distance to receive the proper amount of bonding material.

3. A building block formed of an outer and an inner section of concrete spaced from each other throughout their entire extent, the middle portions of the sections upon their confronting faces being longitudinally recessed from end to end for

their entire length to reduce the thickness of the sections at the middles thereof, the upper and lower ends of the sections being relatively thick, and longitudinally corrugated integral metallic ties of sheet metal extending into the relatively thick portions of the two sections and initially embedded therein. 5

4. A building block formed of an outer and an inner section of concrete, the sections being spaced from each other throughout their entire 10 extent, the middle portions of the sections upon their confronting faces being longitudinally recessed from end to end for the entire length of the section to reduce the thickness of the sections at the middle, the upper and lower ends of the 15 sections being relatively thick to provide relatively thick bearing surfaces abutting against corresponding surfaces of adjacent blocks and upper and lower metallic ties each formed of an integral piece of sheet metal, the ties extending 20 into the relatively thick portions of the two sections and initially embedded therein, the ties being longitudinally corrugated and formed at their opposite ends with perforations to provide means anchoring the ties in the concrete of the 25 sections, the ties being disposed in planes parallel to the planes of the upper and lower surfaces of the sections.

5. A tie for building blocks consisting of a longitudinally corrugated metallic sheet, the ends of 30 the sheet being formed with anchoring projections.

6. A building block having two opposed spaced sections of concrete, ties having their ends embedded in the opposite sections of the block and 35 extending across the space between the sections, each tie being formed of a strip of metal corrugated from end to end and formed adjacent its ends with anchoring perforations having margins projecting beyond the plane of the tie. 40

7. A building block formed of an outer and an inner section of concrete, the sections being spaced from each other along their entire extent, and ties having their ends embedded in the opposite sections of the block and extending across 45 the space between the sections, each tie being formed of a strip of metal corrugated from end to end and formed adjacent its ends with anchoring means, the ties being disposed with their corrugated faces parallel to the upper and lower ends 50 of the sections and disposed adjacent opposite ends of the sections.

CHARLES L. SANFORD.
